VENTILATED CAN COVER

Filed March 23, 1925

2 Sheets-Sheet 2

UNITED STATES PATENT OFFICE.

JULIUS HEUSSER, OF CLEAR LAKE, WISCONSIN.

VENTILATED CAN COVER.

Application filed March 23, 1925. Serial No. 17,790.

To all whom it may concern:

Be it known that I, JULIUS HEUSSER, a citizen of the United States, residing at Clear Lake, in the county of Polk and State 5 of Wisconsin, have invented certain new and useful Improvements in Ventilated Can Covers; and I do declare the following to be a full, clear, and exact description of the invention, such as will enable others skilled 10 in the art to which it appertains to make and use the same.

This application relates to improvements in ventilated can covers and it relates more particularly to covers for milk cans used for 15 permitting the entrance of cool air into the cans and the escape of warm air therefrom to effect cooling of the milk or cream while it is standing, preparatory to shipment.

On March 11th, 1924, a U. S. patent was 20 issued to me on a ventilated cover of the same general type herein disclosed, but it is the object of the present invention to improve upon the construction shown by that patent, the number of which is 1,486,336.

With the foregoing in view, the invention 25 resides in the novel subject matter herein-after described and claimed, the description being supplemented by the accompanying drawings.

Figures 1 and 2 are side elevations looking 30 in different directions and showing the application of the invention to two different types of milk cans.

Figure 3 is an enlarged vertical sectional 35 view as indicated by line 3—3 of Fig. 1.

Figure 4 is a horizontal section as indicated by line 4—4 of Fig. 3.

In the drawings above briefly described, 40 the numeral 1 designates an annular wall whose upper portion is perforated or otherwise screened as indicated at 2, while its lower portion tapers downwardly in the preferred form of construction, to provide a seat 3 which seat may engage either the 45 flared neck of a milk can such as that shown in Figs. 1 and 3, or may rest upon the upper edge of a can of the type shown in Fig. 2. At its lower edge, the wall 1 is provided with an inwardly extending annular flange 4 50 having ventilating openings 5.

Resting upon the upper edge of the wall 1 is an outwardly inclined canopy ring 6 whose edge portion is preferably downwardly offset from its inner portion to provide an 55 annular shoulder 7 engaging the outer side of the wall 1, thus preventing any relative

radial shifting of these two parts. In the preferred formation, the inner edge of the ring 6 is bent upwardly to provide an annular upstanding flange 8. 60

Extending vertically through the central openings of the flange 4 and ring 6, is a warm air escape pipe 9 which projects below said flange and above said ring, the pipe being provided with a rib 10 or other external shoulder resting upon the flange 8. 65 Above this rib, the pipe 9 is perforated as at 11, or otherwise formed to produce a screened air outlet or outlets. Resting upon this perforated upper end of the pipe 9, is 70 a canopy 12 whose inner and outer portions are preferably offset with respect to each other to provide an annular shoulder 13 which surrounds said upper end of the pipe.

A plurality of vertical tie bolts 14 are 75 located within the pipe 9 and in the preferred form of construction, have their lower ends bent outwardly to provide lugs 15 which pass through openings 16 in the pipe and engage the lower side of the flange 4. 80 The upper ends of the lugs 15 are offset and angled as shown in Fig. 3 and pass through openings in the canopy 12, said rods being provided with nuts 17 or equivalent shoulders engaging the top of the canopy. 85 The portions 15^a of the lugs 15, contiguous to the body portions of the rods 14, are preferably of substantially U-shape as shown in Fig. 3, so that the upper edges of the openings 16 can seat therein, thus preventing 90 the lower ends of the rods from moving inwardly and disengaging the lugs from the flange 4.

By constructing the cover in the manner shown, it may be easily manufactured of 95 separate sections and these sections may be readily assembled and secured with respect to each other without the necessity of performing any soldering operation. Moreover, whenever advisable, the entire device may be 100 disassembled for most thorough cleaning and sterilization.

Novel provision is made for connecting the cover with a can upon which it is to be used. 105

I provide two anchors 18 which are adapted to engage the projecting handles H of the type of milk can shown in Figs. 1 and 3, or the bail-attaching lugs L of a can such as that shown in Fig. 2. Elastic connectors, preferably in the form of coiled springs 19, are connected with the anchors 110

18 and extend in opposite directions therefrom, circumferentially of the can cover, the outer ends of these connectors being attached at four circumferentially spaced 5 points 20, to the upper end portion of the wall 1, attachment of said wall and connectors being preferably effected by means of cotter pins, as shown.

By providing the connectors 19 and anchors 18 and associating them with the cover in the manner disclosed, the latter is held down upon the upper end of the can at four points, so that regardless of the type of can upon which the device is used, there is no 10 danger of it tilting and leaving a gap through which flies or other insects may enter the can.

Moreover, when applying or removing the device, the anchors 18 may be held in the 20 operator's hands and pulled radially outward, so that they co-operate with the elastic connectors 19 in supporting the entire cover, and due to the relation of parts shown, the cover will not then turn to an inverted 25 position.

Each anchor 18 is preferably formed of a strip of sheet metal bent into C-shape near its upper end to provide a hook 21 engageable with a can handle H. Under this hook, 30 the strip is further bent into C-shape to form a handle 22 which facilitates engagement of the hook with the can handle, or disengagement therefrom. Between the portions 21 and 22, the metal strip is provided with 35 an inwardly projecting pin 23 which is receivable in the usual bail-engaging opening O in the lug L, as shown in Fig. 2. The pin 23 may well be in the form of a stove bolt passing through an opening in the metal 40 strip, the head of the bolt engaging the outer side of the strip while its nut is clamped against the inner side thereof.

By constructing the device in the manner herein disclosed or in substantially this manner, an article is produced which is greatly advantageous over the device shown by my prior patent, and on account of the advantages for the details disclosed, they are preferably followed. However, within the scope 45 of the invention as claimed, modifications 50 may of course be made.

I claim:

1. A ventilated can cover having a seat to rest on the upper end of a can, a pair of an-

chors to engage projections on opposite sides 55 of the can, and elastic connectors connected with said anchors and extending in opposite directions therefrom circumferentially of the cover, the outer ends of said connectors being connected to said cover at four circum- 60 ferentially spaced points.

2. A structure as specified in claim 1; each of said anchors comprising a strip of metal having a hook and bent below the hook to provide a handle for engaging said hook 65 with or disengaging it from one of the aforementioned projections.

3. A structure as specified in claim 1; each of said anchors comprising a strip of metal bent into C-shape to provide a hook and further bent into C-shape below the hook to provide a handle for engaging said hook with or disengaging it from one of the aforementioned projections.

4. A structure as specified in claim 1; 75 each of said anchors comprising a strip of metal bent into C-shape to provide a hook and further bent into C-shape below the hook to provide a handle for engaging said hook with or disengaging it from one of the 80 aforementioned projections said strip having a rigidly projecting pin between its two C-shaped portions.

5. A ventilated can cover comprising an annular wall adapted to rest on the upper 85 end of a can, said wall being provided at its upper end with ventilating openings and at its lower end with an inwardly extending flange having ventilating openings, a canopy ring resting on said wall, a central heat 90 escape pipe surrounded by said ring and said flange and having air escape openings above the ring, said pipe being provided with an external shoulder resting on said ring and having circumferentially spaced 95 openings adjacent the inner edge of said flange, a canopy resting on the upper end of said pipe, and tie rods within said pipe, said rods having lugs at their lower ends passing through the aforesaid circumferentially 100 spaced openings and engaging the lower side of said flange, the upper ends of said rods passing through said canopy and having shoulders engaging the top of the latter.

In testimony whereof I have hereunto af- 105 fixed my signature.

JULIUS HEUSSER.
